CONTROL MECHANISM

Charles A. Arens, Chicago, Ill., assignor to Arens Controls, Inc., Chicago, Ill., a corporation of Illinois

Application May 31, 1941, Serial No. 395,980

13 Claims. (Cl. 74—501)

This invention relates to control mechanisms, particularly of the type adapted to releasably retain a device to be controlled in a plurality of positions of adjustment.

It is an object of the invention to provide a new and improved control mechanism for releasably retaining a controlled device in a plurality of positions, and more specifically to provide new and improved locking or holding structures for use with such mechanisms.

Still more specifically stated, it is an object of the invention to provide locking or holding structures for control mechanisms of the type defined, which are smoother and more uniform and positive in their gripping and release operations, which are more durable and less susceptible to marring or deterioration, and which are of general improved locking efficiency.

A further object of the invention is to provide, in control mechanisms of the type defined, improved handle and release structures.

Various other objects, advantages and features of the invention will appear from the following specification when taken in connection with the accompanying drawing wherein certain preferred embodiments of the invention are set forth for purposes of illustration.

In the drawing, wherein like reference numerals refer to like parts throughout:

Fig. 1 is a general assembly view of a control mechanism constructed in accordance with the principles of the invention;

Fig. 2 is a longitudinal sectional view of the mechanism of Fig. 1, on an enlarged scale, and illustrating the action of the various operating parts;

Fig. 3 is a view similar to Fig. 2, but showing the locking or holding mechanism in released position;

Fig. 4 is a partial perspective view of the operating sleeve, forming a part of the mechanism of Figs. 1, 2 and 3;

Fig. 5 is a transverse sectional view of the mechanism, on a further enlarged scale, and taken on the line 5—5 of Fig. 2; and

Figs. 6, 7 and 8 are views similar to Fig. 5, but showing modified embodiments of the invention.

Referring more specifically to the drawing, and first to the embodiment illustrated in Figs. 1 to 5 inclusive, it will be seen that the control mechanism 10 comprises in general a main frame or housing sleeve 11, Figs. 1 and 2, an operating sleeve 12 longitudinally slidable within the frame sleeve, and a handle structure generally indicated by the numeral 13. The control mecha-

nism, in the particular embodiment set forth for illustrative purposes, is adapted to operate a controlled device 14 through the intermediary of a transmission cable generally indicated by the numeral 15. More specifically, the transmission cable comprises a flexible sheath 16 and a core member 17 longitudinally slidable within the sheath, one end of the core being connected to the operating sleeve 12 of the control mechanism by suitable means such as a set screw 18. The opposite end of the core is suitably, pivotally secured to the device 14 as indicated at 19, Fig. 1, and it will thus be seen that as the operating sleeve 12 is moved to various shifted positions, corresponding increments of movement will be imparted to the controlled device 14. In Fig. 1 the inward position of the handle and the controlled device is shown in full lines. The position, as the handle is pulled outwardly or to the left as seen in Fig. 1, is shown in dotted lines.

Referring more specifically to the structure of the control mechanism, it will be seen that the housing or frame sleeve 11 is threaded at one end thereof, a pair of nuts 25 and 26 being provided on this threaded end and adapted to cooperatively grip a support structure 21 whereby to secure the frame sleeve thereto. The support structure, may for example be the dashboard of an automotive vehicle or aircraft, in a installation, for example, where the control mechanism is used as a control device for an automotive or aircraft vehicle. A lock washer such as indicated at 28 may be interposed between the nut 27 and the support structure. The nut 26 is provided with an inturned flange 29 positioned against the extreme end of the sleeve 11, and acting as an abutment stop for the inward movement of the handle structure 13, to the right as seen in Figs. 1, 2 and 3.

The means for moving the operating sleeve 12 longitudinally within the housing or frame sleeve 11, comprises a handle member 30 suitably secured to the end of the sleeve 12 for example by a set screw or the like, as indicated at 31. By means of the handle member 30, the operating sleeve 12 may be shifted to various longitudinal positions, whereby to adjustably position the controlled device 14.

The holding means for releasably holding or locking the operating sleeve in its various positions of adjustment comprises in general a control shaft 35, a handle member 36 secured to one end of the control shaft, and a holding element 37 engaged by an inclined cam surface 38 formed on the opposite control shaft end. The holding

or locking element 37 is disposed within an opening 39, Fig. 4, formed in the operating sleeve, and is adapted to be thrust by the cam surface 38 into engagement with the interior surface of the stationary frame sleeve 11. The control shaft 35 is normally thrust outwardly, to the left as seen in Figs. 2 and 3, by a compression spring 40 engageable at one end against a collar 41 loosely mounted on the control shaft but anchored against a shoulder 42 formed on the operating sleeve, the other end of the spring being engageable against a hub 43 formed on the handle member 36. Preferably the handle 36 is secured to the end of the control shaft by means of a threaded connection, as indicated at 44, whereby to permit the adjustment of the parts.

Interposed between the handle members 30 and 36 is a filler member 45, preferably of sponge-rubber or the like, the filler member, together with the handle parts 30 and 36 forming the composite handle structure 13. The resiliency of the filler member somewhat augments the action of the compression spring 40, and also prevents any part of the operator's hand from being caught between the relatively movable handle members. Additionally, the filler member spaces the handle parts 30 and 36 whereby to enable them to be more conveniently gripped and squeezed together by the operator's hand. To facilitate the gripping of the handle structure, the upper portion of the handle member 36 is recessed slightly as indicated at 46, Fig. 1, to receive the thumb bridge, whereas the handle member 30 is provided with recesses 47 and 48 on the upper and lower portions thereof, respectively, to receive the operator's fingers.

The character and shaping of the holding element 37, constituting an important feature of the invention, will be best understood by reference to Fig. 5. As will be seen, the holding element is in the form of a roller provided with a central cylindrical portion or surface 50 and a pair of end surfaces or portions 51 and 52 of generally conical shape, or of truncated conical shape, but having a curvature corresponding to the curvature of the interior surface 53 of the housing sleeve 11. The cam surface 38 on the control shaft 35, while inclined longitudinally, is flat transversely, as will be understood by reference to Fig. 5. Accordingly, it will be seen that the cylindrical surface 50 of the holding element 37 has line contact with the cam surface 38 when in locking or holding position thereagainst, as distinguished from point contact such as would normally be provided were the holding element in the form of a ball. Similarly, the curved conical surfaces 51 and 52, being of a curvature corresponding to the interior surface 53 of the frame sleeve 11, maintain line contact with the frame sleeve when in locking or holding position.

The manner in which the shaping of the holding element may be varied, to best suit the requirements for any particular installation, is illustrated in Fig. 6. In this instance the holding or locking element 37a has its cylindrical surface 50a of a shorter length, as compared with the embodiment previously described, the curved conical surfaces 51a and 52a being correspondingly increased. It will thus be seen that the area of contact between the holding element and the control shaft is decreased, and the area of contact between the holding element and the housing sleeve is increased, with respect to the first described embodiment. In the locking mechanism, the control shaft 35 may be of one kind

of metal and of a certain degree of hardness, whereas the housing or frame sleeve 11 may be of a different metal or of a different degree of hardness. By varying the specific shaping of the holding or locking element, it will be seen that the areas of contact between the parts may be readily controlled and varied to meet the requirements of the particular installation and give the greatest locking efficiency and smoothness of operation.

In the operation of the structure, and referring again to Figs. 1, 2 and 3, normally the compression spring 40 urges the control shaft 35 to the left, to the position of Fig. 2, whereby to cause the cam surface 38 thereon to engage the holding element 37 and wedge it into firm engagement with the internal surface of the frame sleeve 11, thereby holding the operating sleeve 12 in fixed position within the housing sleeve. The force of the compression spring will determine the degree of holding effectiveness, and by varying the spring pressure different degrees of holding action may be secured, grading from a relatively light frictional retention to a substantially positive lock. To release the operating sleeve 12 for movement, whereby to adjust the controlled device 14, the handle structure 13 is gripped and the handle member 36 moved relatively toward the handle member 30, to the position of Fig. 3, thereby compressing the spring 40 and releasing the holding element or roller 37. The operating sleeve 12 may thereupon be moved by means of the handle structure 13 to any desired position. The resilient filler member 45 yields to permit the release of the holding or locking means, and the shaping of the handle members 30 and 36 facilitates their gripping and manipulation.

As previously indicated, the improved form of holding element 37 provides for increased holding or locking efficiency. More particularly, the line contact provided between the holding roller and its engaged surfaces prevents any digging or marring of the parts leading to their undue deterioration. The line or area contact, as distinguished from point contact, decreases the unit engagement pressures in relation to the operating forces, and thus insures that the holding element will not become imbedded or jammed in locking position, even though the operating sleeve is subjected to strong pulling forces. The holding element is at all times immediately releasable without possibility of jamming. The increased contact areas prevent pitting of the housing sleeve, insuring a smooth, reliable and uniform holding action. A stronger and more positive locking action may be obtained, by the increased tensioning of the spring 40, while at the same time avoiding the risk that the increased forces will tend to cause the locking element to become imbedded within the engaged surfaces. The holding element or roller, due to its character, may be proportioned, as heretofore described in reference to Figs. 5 and 6, so as to obtain the precise areas of contact with the engaged surfaces giving the desired operating characteristics for the particular installation.

In Fig. 7 an embodiment is illustrated wherein the holding element 37b is in the form of a ball, but wherein the housing sleeve 11b and the control shaft 35b are both so shaped as to provide line or surface contact between the parts. More particularly, in this instance the housing sleeve is provided with a struck-out portion or rib 60 extending longitudinally of the housing over that length thereof which cooperates with and is

adapted to be engaged by the locking element. The interior surface 61 of the rib conforms to the curvature of the holding ball 31b. Accordingly in all shifted positions of the operating sleeve 12b, line or surface contact between the ball and the housing sleeve will be established upon the application of the holding engagement. Similarly the inclined cam surface of the control shaft 35b which engages the ball, is in this instance provided with a longitudinal trough 62, the transverse curvature of which is shaped to correspond to the radius of curvature of the ball surface, so that line or surface contact is maintained between the ball and the control shaft when the parts are in the holding position.

In Fig. 8 an embodiment of the invention is illustrated wherein the housing sleeve 11c and the operating sleeve 12c, in the vicinity of the holding element, are of polygonal shape, specifically square in the illustrated embodiment, rather than of circular cross-section. In this instance the control shaft 35c may be circular in cross-section, and shaped and constructed as described in reference to the embodiment illustrated in Figs. 1 to 5 inclusive; but, as stated, the operating sleeve and the housing sleeve, in the vicinity of the holding element 37c, are of square shape, and slideable, one within the other. In this instance the surface 50c of the holding element may be cylindrical to cooperate with the control shaft in the manner described for example with reference to Fig. 5, whereas the end surfaces 51c and 52c of the holding element, while conical, will be flat or non-curved for cooperation in line contact with the flat interior surfaces 53c of the housing sleeve.

Referring for example to Fig. 2, it will be understood that a considerable proportion of the holding action between the operating sleeve and the housing sleeve, when in held or locked position, occurs at the point indicated by the numeral 70, in addition to the frictional locking action of the element 37 itself. In other words, the element 37 reacts against the end of the control shaft 35, and the latter in turn presses downwardly on the operating sleeve, forcing the operating sleeve into engagement with the housing or frame sleeve, into frictional contact, at the point 70 and in the adjacent areas. Where the sleeves are circular in shape it will be seen, referring to Fig. 5, that only a limited area of contact extending longitudinally of the sleeves will be firmly engaged, this area being at the lowermost point on the sleeves. On the other hand, referring to Fig. 8, it will be seen that when the sleeves are polygonally shaped, extended contact surfaces as indicated at 70c are provided between the sleeves, such contact surfaces being substantially half of the sleeve areas. Due to the increased contact areas, a smoother locking action is possible.

It is obvious that various changes may be made in the specific embodiments set forth for purposes of illustration without departing from the spirit of the invention. The invention is accordingly not to be limited to the specific embodiments shown and described, but only as indicated in the following claims.

The invention is hereby claimed as follows:

1. A control mechanism comprising a frame member adapted to be secured to a support, said frame member having an arcuate locking surface, an operating member shiftable relative to the frame member and adapted to be connected to a device to be controlled, and holding means

for releasably holding the operating member from movement with respect to the frame member, said holding means comprising an inclined cam surface, and a rollable holding element controlled by said surface and adapted to be forced thereby into engagement with the arcuate locking surface of the frame member, said holding element having line contact with said cam surface and with the engaged arcuate surface of the frame member.

5 2. A control mechanism comprising a circular frame sleeve adapted to be secured to a support, an operating member shiftable within the frame sleeve and adapted to be connected to a device to be controlled, and holding means for releasably holding the operating member from movement with respect to the frame sleeve, said holding means comprising an inclined cam surface, and a holding element controlled by said surface and adapted to be thrust thereby into engagement with the interior circular surface of the frame sleeve, said holding element having line contact with said inclined cam surface and with the engaged circular surface of the frame sleeve.

15 3. A control mechanism comprising a circular frame sleeve adapted to be secured to a support, an operating member shiftable within the frame sleeve and adapted to be connected to a device to be controlled, and holding means for releasably holding the operating member from movement with respect to the frame sleeve, said holding means comprising an inclined cam surface, and a holding element controlled by said surface and adapted to be thrust thereby into engagement with the interior surface of the frame sleeve, said holding element comprising an elongated roller member having line contact with said inclined cam surface and with the engaged surface of the frame sleeve.

20 4. A control mechanism comprising a frame member adapted to be secured to a support, an operating member shiftable relative to the frame member and adapted to be connected to a device to be controlled, and holding means for releasably holding the operating member from movement with respect to the frame member, said holding means comprising an inclined cam surface, and a rollable holding element controlled by said surface and adapted to be forced thereby into engagement with the frame member, said holding element having one portion thereof shaped to conform to the inclined cam surface and another portion thereof shaped to conform to the engaged surface of the frame member 25 whereby to maintain line contact with both of said surfaces.

5. A control mechanism comprising a circular frame sleeve adapted to be secured to a support, an operating member shiftable within the frame sleeve and adapted to be connected to a device to be controlled, and holding means for releasably holding the operating member from movement with respect to the frame sleeve, said holding means comprising an inclined cam surface, and a holding element controlled by said surface and adapted to be thrust thereby into engagement with the interior surface of the frame sleeve, said holding element comprising a roller member having a central cylindrical portion engageable with the inclined cam surface, and conical end portions shaped to conform to the curvature of the interior surface of the frame sleeve and engageable therewith.

6. A control mechanism comprising a frame sleeve adapted to be secured to a support, an

operating member shiftable within the frame sleeve and adapted to be connected to a device to be controlled, and holding means for releasably holding the operating member from movement with respect to the frame sleeve, said holding means comprising an inclined cam surface, and a holding element controlled by said cam surface and adapted to be thrust thereby into engagement with the interior surface of the frame sleeve, said holding element comprising a roller having a central cylindrical portion engageable with the cam surface, and conical end portions engageable with the interior surface of the frame sleeve.

7. A control mechanism comprising a frame member adapted to be secured to a support, an operating member shiftable relative to the frame member and adapted to be connected to a device to be controlled, and holding means for releasably holding the operating member from movement with respect to the frame member, said holding means comprising a shiftable control member, an inclined cam surface, and a holding element controlled by said surface, a handle secured to the operating member, a handle secured to the control member, said handles having portions in longitudinally spaced relation at their peripheries, and a filler member of compressible resilient material arranged between the handles and filling the space therebetween.

8. A control mechanism as defined in claim 7 wherein said handles and said filler member are of substantially the same cross sectional area whereby to provide a composite handle structure substantially uniform in transverse cross section.

9. A control mechanism comprising a frame member adapted to be secured to a support, an operating member shiftable relative to the frame member and adapted to be connected to a device to be controlled, and holding means for releasably holding the operating member from movement with respect to the frame member, said holding means comprising an inclined cam surface, and a holding element controlled by said surface and adapted to be forced thereby into engagement with the frame member, said holding element comprising a spherical ball having line contact with said inclined cam surface and with the engaged surface of the frame member.

10. A control mechanism comprising a circular frame sleeve adapted to be secured to a support, an operating member shiftable within the frame sleeve and adapted to be connected to a device to be controlled, and holding means for releasably holding the operating member from movement with respect to the frame sleeve, said holding means comprising an inclined cam surface, and a holding element controlled by said surface and adapted to be thrust thereby into engagement with the interior surface of the frame sleeve,

5 said holding element comprising a spherical ball member, and said inclined cam surface and the engaged surface of the frame sleeve having portions thereof shaped to conform to the curvature of said ball member.

11. A control mechanism comprising a polygonal frame sleeve adapted to be secured to a support, an operating member shiftable within the frame sleeve and adapted to be connected to a device to be controlled, and holding means for releasably holding the operating member from movement with respect to the frame sleeve, said holding means comprising an inclined cam surface, and a holding element controlled by said inclined cam surface and adapted to be thrust thereby into engagement with the interior surface of the frame sleeve, said holding element being engageable into one of the angular apexes of the frame sleeve and having portions shaped to conform to the engaged sleeve surfaces.

15 12. A control mechanism comprising a polygonal frame sleeve adapted to be secured to a support, a polygonal operating sleeve shiftable within the frame sleeve and adapted to be connected to a device to be controlled, and holding means for releasably holding the operating sleeve from movement with respect to the frame sleeve, said holding means comprising a control shaft shiftable within the operating sleeve and having an inclined cam surface, and a holding element controlled by said surface and adapted to be thrust thereby into engagement with the interior surface of the frame sleeve, said holding element being disposed within an opening in the operating sleeve, the opening being arranged in one of the angular apexes of the operating sleeve, and said holding element comprising a roller having a central cylindrical portion adapted to engage the control shaft inclined cam surface, and conical end portions shaped to conform to and adapted to engage the interior surface of the frame sleeve.

20 13. A control mechanism comprising a frame member adapted to be secured to a support, an elongated operating member axially shiftable relative to the frame member and adapted to be connected to a device to be controlled, and holding means for releasably holding the operating member from movement with respect to the frame member, said holding means comprising an elongated control member axially shiftable with respect to the operating member, a handle secured to the operating member, a handle secured to the control member, said handles having portions in longitudinally spaced relation at their peripheries, and a filler member of compressible resilient material arranged between the handles and filling the space therebetween.
